INVENTOR
MAURICE B. BLEHERT
BY *Andrew C. Carleen*
ATTORNEY

UNITED STATES PATENT OFFICE

MAURICE B. BLEHERT, OF ST. PAUL, MINNESOTA

GARMENT

Application filed August 20, 1932. Serial No. 629,578.

This invention relates to garment designs and the main or primary object is to provide a novel arrangement of drop seat and devices including belt sections for releasably securing the drop seat in place. The invention is particularly adapted for use in children's garments such as coveralls, snow suits, sleeping garments, underwear, pants, play suits, etc., but is obviously also adaptable for use in various types of garments for adult use. I am aware of numerous types of prior art garments having drop seat and belt securing devices of various forms, but in no such instance have I found permanently secured belt section ends and sliding loop arrangements as herein disclosed or having the particular advantages which are found in the present invention. The features and advantages in question will be fully disclosed in the course of the following specification, reference being had to the accompanying drawing, wherein:

Fig. 1 is a front elevation of a garment embodying my invention.

Fig. 2 is a left side elevation of the garment as shown in Fig. 1, with the drop seat in its raised position and a fractional portion broken away for purpose of illustration.

Fig. 3 is a side elevation similar to Fig. 2 but showing the drop seat in its lowered position.

Fig. 4 is an enlarged sectional plan view on the line 4—4 in Fig. 3, with the drop seat in partially open position.

Fig. 5 is an enlarged fractional detail perspective elevation of the front portion of one of the belt sections.

Fig. 6 is a detail section on the line 6—6 in Fig. 5.

Referring to the drawing more particularly and by reference characters, Figs. 1 to 4, inclusive, show a union type of garment having arms 7, legs 8, an openable front 9, and a drop seat 10 which, when closed, overlays a lower extension 11 of the back section 12. The drop seat 10 has free lateral edges 13, to permit a full drop of the seat, and the upper end edge of the drop seat is preferably reinforced by a belt or belt simulating hem 14.

Lateral belt sections 15 have outer terminal ends permanently sewed or otherwise suitably secured to the ends of the member 14, or at the upper free corners of the drop seat, as at 16; while the inner terminal ends of these 55 belt sections are permanently secured, as at 18, to the sides of the garment and preferably immediately under side loops or straps 19 also fixed to the sides of the garment proper. Intermediate portions of the belt sections 15 are 60 threaded forwardly through the straps 19 so as to provide loops 20 for sliding engagement, in the present instance, with metal connectors 21. These connectors are joined by supplemental belt loop straps 22 to interlocking 65 buckle members 23. The members 22 are adjustable as to length in the buckles 23 to thereby provide means for effectively regulating the girth size of the belt as a unit, as with the belt section ends 16 and 18 permanently secured to the garment no other adjustment is provided. However, where elastic, or other positive forms of adjustment can be used, or if no adjustment provisions are 70 found necessary, each connector 21 may be 75 made as a part of a buckle 23, i. e., the buckles 23 may be provided with bars or loops to engage directly with the loops 20, thus eliminating the elements 22 when feasible to do so. The connectors 21, or at least the buckles 23 80 are preferably of a size that will permit them to act as stops to prevent the belt sections from being drawn completely through the straps 19. It may be noted, however, that with some types of garments it is practical to 85 dispense with the straps 19 entirely, in which event the tautness of the belt members around the wearer's waist line is relied upon to hold the drop seat up, and in this event the size of the metal parts is of course immaterial.

It may here also be mentioned that in certain types of garments, such as children's undergarments where access to the belt connecting members is more readily made from the 95 rear the belt section loops 20, instead of being brought forward, may be swung rearwardly so that the buckles 23 will meet at the rear of the body. In such instances the presence of the loop straps 19 is most essen- 100

tial as the belt sections must of course be maintained against the garment sides in order to effect the necessary forward pull at the free corners of the drop seat.

5 As a further novel feature and noteworthy advantage in the garment as hereinabove set forth, I wish to point out that the belt construction as disclosed permits of a relatively greater drop movement to the drop seat than is permissible in other generally similar garments, and this because of the fact that because of the loop arrangement 20 the drop seat can move down just twice the distance of movement by each connector 21, after 15 the buckles 23 have been opened, thus utilizing substantially twice the belt length between points 19 and 21 to maintain the connection between points 19 and 16 when the seat is down. And, conversely, it will only 20 require relatively short forward movements of the members 21 (or devices 21-23) to completely restore all the parts to their normal positions as shown in Figs. 1 and 2.

It is understood that suitable modifications 25 may be made in the structure as disclosed, provided such modifications come within the spirit and scope of the appended claims.

Having now therefore fully illustrated and described my invention, what I claim to be 30 new and desire to protect by Letters Patent is:

1. The combination with a garment having a drop seat, of a pair of belt sections having corresponding ends permanently secured to 35 upper corners of the seat and having their opposite ends permanently secured to corresponding points at opposite sides of the garment proper, and separable connector devices slidably engaging portions of the belt sections intermediate the respective ends of each.

2. A garment having a drop seat, belt sections at opposite sides of the garment having corresponding ends attached to the drop seat for holding the latter up in position, and 45 having their other ends attached to the garment proper, and separable connector devices slidably engaging intermediate portions of the belt sections.

3. A garment having a drop seat, belt sections at opposite sides of the garment having corresponding ends attached to the drop seat for holding the latter up in position, and having their other ends attached to the garment proper, and separable connector devices 55 slidably engaging intermediate portions of the belt sections, said drop seat being lowerable upon separation of said connector devices and without detaching the belt sections from said points of end attachment to the garment and to said drop seat.

4. A garment having a drop seat, belt sections at opposite sides of the garment having corresponding ends attached to the drop seat for holding the latter up in position and 65 having their other ends attached to the gar-

ment proper, and having portions intermediate said ends doubled to form connectable loops, and adjustable connector devices for releasably connecting said loops.

5. A garment having a drop seat, belt sections at opposite sides of the garment having corresponding ends attached to the drop seat for holding the latter up in position having their other ends attached to the garment proper, and having portions intermediate 70 said ends doubled to form connectable loops, and adjustable connector devices for releasably connecting said loops, said connector devices including buckles, units for slidably engaging the loops, and flexible members connecting said buckles and units.

6. A garment having a drop seat and having belt guides at opposite sides of the garment, belt sections having corresponding ends attached to the drop seat and other ends attached to the garment proper, intermediate 85 portions of said belt sections being slidable in said belt guides and doubled to form connectable loops, and devices for detachably connecting said loops.

7. A garment having a drop seat and having belt guides at opposite sides of the garment, belt sections having corresponding ends attached to the drop seat and other ends attached to the garment proper, intermediate 95 portions of said belt sections being slidable in said belt guides and doubled to form loops which when the belt sections are drawn through the guides will be operative to sustain the drop seat in its raised position, and releasable means for securing the belt sections in such drawn positions.

8. A garment having a drop seat and having belt guides at opposite sides of the garment, belt sections having corresponding ends attached to the drop seat and other ends attached to the garment proper, intermediate portions of said belt sections being slidable in said belt guides and doubled to form loops which when the belt sections are drawn through the guides will be operative to sustain the drop seat in its raised position, and adjustable devices for releasably securing the belt sections with the drop seat in its raised position.

9. A garment having a drop seat and having belt guides at opposite sides of the garment, belt sections having corresponding ends attached to the drop seat and other ends attached to the garment proper, intermediate 120 portions of said belt sections being slidable in said belt guides and doubled to form loops which when the belt sections are drawn through the guides will be operative to sustain the drop seat in its raised position, and separable connector devices slidably engaging said belt loops.

Signed at Minneapolis, in the State of Minnesota, this 18th day of August, 1932.

MAURICE B. BLEHERT.
